UNITED STATES PATENT OFFICE

WILLIAM H. ROBERTSON, OF DAYTON, OHIO, ASSIGNEE, BY MESNE ASSIGNMENTS, TO THE NATIONAL CASH REGISTER COMPANY, OF DAYTON, OHIO, A CORPORATION OF MARYLAND

CASH REGISTER

Application filed September 18, 1924. Serial No. 738,451.

This invention relates to improvements in cash registers and has more particular relation to the type of machine shown and described in Letters Patent of the United States granted to Thomas Carney, No. 497,860, dated May 23, 1893, and in the copending application of Edward J. Von Pein, Serial No. 293,141, filed April 28, 1919.

One of the objects of the invention is to provide a machine for printing a number of items, together with the total of the items, on an insertable slip, and to provide a positive means for setting the total printing type carriers.

Another object of the invention is to provide mechanism for engaging the totalizer with the actuator segments of the totalizer registering frames and for unlocking the registering frames during total printing operations.

Another object of the invention is to provide a mechanism for selecting one of a plurality of totalizers for printing totals and for resetting them to zero.

Another object of the invention is to provide two sets of type wheels so arranged that substantially the same mechanism can be used for setting both sets during item or total printing operations, and so engraved that they will be set complementary to each other.

With these and incidental objects in view, the invention consists of certain novel features of construction and combinations of parts, the essential elements of which are set forth in appended claims and a preferred form or embodiment of which is hereinafter described with reference to the drawings which accompany and form part of this specification.

Of said figures:

Figs. 1A and 1B taken together constitute a plan view of the machine.

Fig. 26 is a detail view showing the spring-pressed plunger for engaging the "grand" totalizer.

Fig. 27 is a right hand elevation of the "grand" totalizer.

In general the machine includes three groups of keys and two totalizers. The right hand totalizer is used for accumulating the totals of transactions, and is set to zero at the end of each transaction. This totalizer will be hereinafter referred to as the transaction totalizer. The left hand totalizer is used for accumulating the totals of a number of transactions, and will be hereinafter referred to as the grand totalizer.

The present machine is shown adapted for printing on an insertable slip. However, the usual issuing receipt can be provided, if desired. The depression of any one of the keys unlocks and actuates one of the registering frames and adds the amount in the totalizers. This amount is set up on item printing wheels and printed on the slip. When all of the items of the transaction have been entered in the totalizers a crank is operated for setting up the amounts accumulated in the transaction totalizer, on a set of total printing wheels, by the ordinary totalizer registering frames. A special means for engaging this totalizer with the actuators during total printing operations, and also to unlock the totalizer registering frames, is provided. The totalizer wheels are turned to zero by the usual and well known mechanism shown and described in the above mentioned Von Pein application. In turn-to-zero mechanism of this type the wheels are turned in the same direction when being reset, as when receiving items, a distance equal to the complement of the amount therein. After the total printing wheels have been set a special hammer is operated to make an impression on the inserted slip.

A selecting lever is provided to throw out the transaction totalizer and to throw in the

grand totalizer for printing the totals of a number of transactions.

The present machine is capable of performing item entering operations, total printing operations, and grand total printing operations. The mechanism will be described for the various operations in the order named.

Item entering operations

The machine is provided with three groups of keys 30 (Figs. 1A, 1B and 6), having the usual actuator controllers 31 with notches 32 adapted to engage a rod carried by a registering frame 33, one for each group of keys, each of them having secured thereto an actuator segment 34. Each actuator segment 34 is always in mesh with a pinion 35 (Figs. 3 and 6) secured to one end of a sleeve 36, the other end of said sleeve having secured thereto a pinion 95 to which is secured one of the type wheels 38 (Fig. 19). The notches 32 in the actuator controllers 31 are so located that the registering frame will be rocked a distance commensurate with the key depressed.

Type wheel setting means

When the registering frame is rocked by the depression of an amount key 30, the movement given to the registering frame is transmitted to the type wheel 38 (Fig. 19), by the actuator segment 34, pinion 35 meshing therewith, and the sleeve 36 to which the type wheel is secured. Thus depression of an amount key sets up an amount on the type wheel 38 commensurate with the value of the key depressed.

Registering frame lock

The registering frames are locked in their normal positions so as to prevent accidental movement when the actuator controllers are disengaged therefrom. There is a rod 40 loosely mounted in each registering frame (Figs. 6 and 22) and each of said rods has secured thereto two arms 41. One of the arms 41 has an extension 42 contacting a shoulder on a back frame 43 carried by the side frames 44 to prevent movement of the registering frame. Each of the actuator controllers 31 has a rearwardly projecting cam edge 45 which engages the bottom of the back frame 43 during the upward movement of the controllers 31, thus camming the controllers towards the front of the machine to contact a rod 46 carried by the abovementioned arms 41. This forward movement of the actuator controllers 31 moves the extensions 42 out of contact with the frame 43 to permit differential movement of the registering frame 33 when the shoulder 32 strikes the rod 40.

A link 47 is provided to unlock the registering frame 33 during total printing operations. The method of operating this link will

be described when considering the total printing operation. The forward end of the link is provided with a slot 48 surrounding a stud on an arm 165. This slot permits forward movement of the link during item entering operations without affecting the arm 165.

Transaction totalizer engaging mechanism

The mechanism, as shown in the present application, is so constructed that both totalizers will be engaged with the registering frames upon depression of the keys. The engaging mechanism for the transaction totalizer will now be described. A key coupler 50 (Fig. 17), pivoted in the side frames 44 carries a roller 51 adapted to operate the well known double-faced rack 52, (to be later described in detail), which gives the cam shaft 53 a complete rotation when any of the keys 30 are operated. Secured to the shaft 53 (Fig. 6) is a cam 54 adapted to engage two rollers carried on a totalizer engaging lever 55 pivoted on a totalizer frame 56 and adapted to engage a spring-pressed plunger 57, also mounted in the transaction totalizer frame 56. The transaction totalizer frame 56 is pivoted at 58. When its cam shaft 53 is rotated, the lever 55 engages the plunger 57 and rocks the transaction totalizer frame 56, thereby meshing the pinions 59 with the actuator segments 34 of the registering frames. The pinions 59 are secured to totalizer wheels 60. From this it can be seen that when any of the keys 30 are depressed the registering frames are actuated to enter an amount in the transaction totalizer commensurate with the amount of the keys depressed.

As above mentioned the cam shaft 53 is rotated by the double-faced rack 52 (Fig. 17), which rotation is effected in the following manner. When an amount key is depressed, and the key coupler 50, through the roller 51 elevates the rack 52, the pinion 151, loosely mounted on the shaft 53, is rotated clockwise. A disk 149 (Figs. 14 and 15) is sleeved to the pinion 151 and rotates therewith. The disk 149 has pivoted thereon a coupling pawl 148, which pawl has a pin 147 projecting through a slot 146 in a disk 145, pinned on the shaft 53. A spring 144 wound around the shaft 53, holds the pawl 148 and stud 147 in the position shown in Fig. 16. A stud 143 limits the movement of the pawl 148 under the action of the spring 144.

When the rack 52 is elevated to turn the pinion 151, a one-half rotation, the disk 149 is rotated therewith, and the disk 145 and shaft 53 also rotate with the pinion 151 due to the coupling stud 147, which acts to couple the disk 149 to the disk 145. Just before the rack starts on its return, or downward, movement, the spring tension pawl 142 (Fig. 17), in the usual and well known manner, shifts the rack 52 to the right, to mesh the left hand teeth of the double rack 52 with the

pinion 151. Upon subsequent downward movement of the rack 52, the pinion 151, and the disks 149 and 145, are given another one-half rotation, thus completing the full rotation of the shaft 53.

During adding operations, the disks 149 and 145 are not necessary, as the pinions can be pinned directly on the shaft 53, as shown in the Von Pein application referred to. But, in the present machine it is necessary to slightly rotate the shaft 53 to move the totalizer pinions 59 into mesh with the actuator segments 34 during total taking operations. Preferably this meshing of the totalizer is accomplished during total taking operations, without elevating the rack 52 and key coupler 50, and for this reason the disks 149 and 145 are provided, the disk 145 being given a movement without moving the disk 149. The manner in which this result is obtained is later described when considering the total taking operation of the machine.

Means is provided for locking the registering frames for the transaction totalizer until the pinions 59 are engaged with the actuator segments 34. The segments 34 have downward projections 65 (Fig. 6) cooperating with a cam 66 (Figs. 4, 5 and 6) mounted on the cam shaft 53. This cam is so timed that the projection 65 is engaged by the high part thereof until the pinions 59 engage the actuator segments 34, at which time the actuator segments are free to be actuated by the actuator controllers 31.

The actuator segment 34 for the units wheel in the transaction totalizer is secured to the totalizer registering frame 33, as above described. The segment for the tens wheel is loosely mounted on a shaft 70 (Figs. 1A, 1B and 6), carried by the side frames 44, and meshes with a pinion 71 (Fig. 1-B), pinned to a shaft 72 carrying a pinion 73 (Fig. 1-A), meshing with a segment 34', similar to the actuator segment 34, secured to the totalizer registering frame 33 for the tens bank of keys. The registering frame for the dollars group is also loosely mounted on the shaft 70 and meshes with a pinion 74 (Fig. 1-B), secured to a shaft 75, which has secured thereto a pinion 76 (Fig. 1-A), meshing with a segment 34' secured to the totalizer registering frame 33 for the dollars bank of keys.

Grand totalizer engaging mechanism

As before mentioned, the machine is provided with a "grand" totalizer, in addition to the above described "transaction" totalizer. The "grand" totalizer is of the same construction as the "transaction" totalizer above described, except that it has a larger capacity, it having seven totalizer pinions 59' (Fig. 1-A), instead of five pinions 59 (Fig. 1-B), as in the case of the "transaction" totalizer. Each "grand" totalizer pinion 59' has a corresponding totalizer wheel 60'. The engag-

ing mechanism for the "grand" totalizer is exactly like that described for the "transaction" totalizer, and therefore, no further description thereof is believed necessary, the machine being provided with duplicate means for engaging the "grand" totalizer.

The item entering mechanism for the "grand" totalizer is actuated at the same time as the item entering mechanism for the "transaction" totalizer, the two sets of mechanisms being connected to move in unison in a manner old in the art, but which will be briefly described.

The actuator units segment 34' for the grand totalizer is secured to the totalizer registering frame 33 for the units group of keys 30, by means of a yoke 80 (Fig. 1A). The tens actuator segment 34' of the grand totalizer meshes with the above described pinion 73. The dollar segment 34' of the grand totalizer meshes with the above described pinion 78. It can therefore be seen that during item-entering operations both totalizers will be rocked into engagement with the actuator segments 34 and 34' and both will be actuated simultaneously to receive an amount commensurate with the keys depressed.

Transfer mechanism

The transfer, or carrying, mechanism is identical with that shown and described in the above mentioned Von Pein application, and therefore only a brief description will be given herein. The only difference in construction between the present transfer mechanism and the one shown in the above mentioned application is that the transfer cams 85 (Figs. 4, 5 and 6) are all integral with the cam 66. In transfer mechanism of the present type, heretofore disclosed, the transfer cams 85 and the locking cams 66 were separate. In the present machine the projections 65 are formed on the actuator segments 34 and 34', which permits the transfer cams 85 and the locking cam 66 to be made in a unit.

The cams 85 (Fig. 11) are adapted to engage well known carrying pawl supporting levers 86 for the transaction totalizer having 50 loosely mounted thereon the usual carrying pawls 87 adapted to engage ratchets 88 secured to the totalizer wheels 60. A long tooth 89 is provided to trip a transfer trip pawl 90 when going from "9" to "0" to permit the carrying pawl 87 to engage the ratchet 88 of the next higher order wheel when the cam 85 operates the carrying pawl supporting lever 86. A duplicate set of cams (not shown, but like the cams 85) is provided 55 to actuate the carrying pawl supporting levers 86' (Fig. 1A) and carrying pawls 87' for the "grand" totalizer. However, since there are six carrying pawl supporting levers 86', six cams (not shown) like the cams 85, 65 are provided for the "grand" totalizer.

Type wheel aligner

After the type wheels 38 are positioned by the actuator segments 34 of the totalizer registering frames, as above described, they are aligned by mechanism which will now be described. Each pinion 95 (Fig. 19), meshes with a pinion 96 loosely mounted on a shaft 97 carried by printer frames 98 and 99 (Fig. 1B). Secured to the end of the shaft 53 (Figs. 19, 20 and 25) is a cam 100 engaged by a roller on a downwardly projecting arm 101 of a lever 102. A spring 104 (Fig. 25), stretched between a stud 105 on a rearwardly projecting arm 106 of the lever 102 and a stud in the frame 98, holds the roller on the arm 101 against the cam 100. The lever 102 and lever 107 (Figs. 19 and 20) are connected by an aligning bar 103. When any of the keys 30 are depressed and the shaft 53 is rotated, the cam 100 rocks the bar 103 far enough to engage the pinions 96. The cam 100 is so timed that this engagement takes place just before the item printing platen makes an impression on the inserted slip. It will be noticed that the lever 107 has connected thereto a pitman 109. This pitman is operated during total printing operations by a cam 110. The purpose of this mechanism will be described when considering the total-printing operations. It is sufficient to state here that the cam 110 has a notch 111 to permit the bar 103, when operated by the cam 100, to engage the pinions 96.

Item printing hammer

The means for making an impression from the item type wheels 38 during item entering operations will now be described. Secured to the shaft 53 (Fig. 10) is a cam 115 adapted to operate a spring-pressed hammer arm 116 which carries at its outer end a platen 117 (Fig. 19). The cam 115 is so timed that the platen 117 makes an impression on the inserted slip from the type wheels 38 after the type wheels 38 have been aligned by the mechanism above described. This impression mechanism is all old and well known, and is shown and described in the above mentioned Von Pein application, and it is thought 115 that this brief description is sufficient.

Slip feeding mechanism

The usual and well known means for spacing the printed items after each impression has been made is provided, and only a brief description will be given herein. A feed roller 120 (Fig. 19) is engaged by a tension roller 121 mounted on a spring-tensioned arm 122. This construction permits the tension roller 121 to be disengaged from the feed roller 120 for inserting the slip. The feed roller 120 has secured thereto a ratchet 128 engaged by a feed pawl 123, pivoted to an arm 124, fast on an arm 125 (Fig. 10), secured to a 130

short shaft 126 of the key coupler 50. When the key coupler 50 (Fig. 6) is given a rocking movement by any of the keys 39, the arm 124 (Fig. 19) operates the pawl 123 and thereby feeds the slip far enough to space the printing, as shown in Fig. 8. A retaining pawl 127 is provided to prevent retrograde movement of the feed roller 120 and is adapted to engage the above mentioned ratchet wheel.

Inking ribbon

An endless ribbon 130 (Fig. 19) is provided, which is fed by the usual well known mechanism, shown and described in the above mentioned Von Pein application. It forms no part of the present invention and it is therefore thought that a disclosure herein is unnecessary. The ribbon is fed between the type wheels and printing platens, to make the impression on the inserted slip legible.

Transaction total printing operations

After the items have been entered in the totalizers the transaction totalizer is turned to zero, and the total which was accumulated thereon is printed on the inserted slip. The turn-to-zero mechanism is utilized for setting up the total printing type wheels. Before turning the transaction totalizer to zero, it is engaged with the actuator segments 34, which segments are constantly in mesh with the above described pinions 35 for setting the item type wheels 38. It will be remembered that the item type wheels 38 are secured to the pinions 95 which mesh with pinions 96. The pinions 96 mesh with pinions 140 secured to the side of total-printing type wheels 141. From this it can be seen that after the totalizer is engaged with the actuating segments 34, and is turned to zero by mechanism to be hereinafter described, the movement of the totalizer is transmitted to the total-printing wheels 141 in the following manner. The item type wheels and the total type wheels are both set up on every operation. On item entering operations they are returned to zero so that at the beginning of the total printing operations both sets always stand at zero. When the totalizer is reset to zero during total printing, the totalizer wheels are rotated in the same direction as when adding until they rest at zero. This will, of course, set up on the item printing wheels the complement of the amount on the totalizer. As the total printing wheels are directly geared to the item wheels they will be moved to the same extent and in the same direction but as the numerals on the total wheels are engraved in the reverse direction about the peripheries of these wheels, the amount which stood on the totalizer and not its complement will be set up and printed. By this arrangement the total printing wheels are set by a positive

means and with the use of a minimum number of parts.

Totalizer engaging mechanism

It will be remembered that during item-entering operations the shaft 53 is given a complete rotation by the rack 52. However, during total-printing operations the rack 52 is not operated. A mechanism is provided for giving the shaft 53 a slight counter-clockwise movement for engaging the totalizer pinions 59 with the actuator segments 34 during total-printing operations and this mechanism will now be described. Secured to the shaft 53 is the previously mentioned disk 145 (Figs. 13, 15 and 16) having the slot 146 cut therein, through which projects the pin 147 mounted on the pawl 148 carried by the disk 149 (Figs. 14 and 15) loosely mounted on the shaft 53, and secured to the pinion 151, operated by the double-faced rack 52. The pin 147 also projects into a cam slot 154 of an arm 155 (Fig. 13) which is operated by a pair of cams 156 secured to a cam shaft 157. The cam shaft 157 is given a complete rotation in the direction shown by the arrow (Fig. 13) during each total-printing operation by the operating crank 158 (Fig. 19), secured to a sleeve clutched to a pinion 159 meshing with a gear 160 secured to the shaft 157. During total-printing operations the pawl 148 is rocked counter-clockwise to cam the disk 145, together with the shaft 53, in a counter-clockwise direction.

The movement given the shaft 53 by the arm 155 is sufficient to rock the cam 154 far enough to engage the transaction totalizer pinions 59 with the actuating segments 34 and to disengage the cam 66 from the projections 65 of the registering segments 34. At the end of the operation the shaft 53 is returned to home position by the arm 155.

This mechanism provides a convenient means for slightly rotating the shaft 53, without elevating the double rack 52, thus reducing the load on the operating handle 158 to a minimum. If it were not for the loose connection between the shaft 53 and pinion 151, and double rack 52, it would be necessary to not only lift the rack 52 but to also raise the key coupler 50. The key coupler has no function during total printing operations and therefore, it is unnecessary to place this added load on the handle 158 during such total taking operations.

Registering segment unlocking mechanism

After the totalizer pinions have been engaged with the registering segments it is necessary to disengage the locking extension 42 of the arms 41 (Figs. 6 and 22) from the shoulder on the back frame 43. The before mentioned link 47 is moved by a stud in an arm 165 secured to a shaft 166. There is a link 47 and an arm 165 for each registering

frame. Also secured to the shaft 166 is an arm 167 (Fig. 13) bifurcated to embrace a stud 168 mounted on the arm 155. When the arm 155 is rocked by the cams 156 the links 47 are pulled toward the front of the machine to disengage the locking extensions 42 of the arms 41 from the back frame 43. The timing of the cam 156 is such that the arm 41 is disengaged from the frame 43 after the totalizer 10 has been engaged with the actuator segments 34.

Turn-to-zero mechanism

After the transaction totalizer has been engaged with the actuator segments, as above described, the totalizer wheels are turned to zero. This turn-to-zero mechanism will now be described. Secured to the shaft 157 (Fig. 10) is a cam 175 having a cam groove into which a roller on an arm 176 projects. The arm 176 is pivoted on a shaft 177 carried by the right side frame 44 of the printer frame 98. The arm 176 is connected to a segment 178 by means of a link 179. The segment 178 meshes with a pinion 180 secured to a ratchet 181, pinned to a shaft 182. The ratchet 181 is engaged by a spring-pressed pawl 183 pivoted on a disk 184 secured to a gear 185 loosely mounted on the shaft 182. The gear 185 meshes with a pinion 186 pinned to a shaft 187 (Figs. 1B, 10 and 22). The shaft 187 is flexibly connected to the totalizer shaft 188 by a universal coupling 189. The shaft 188 (Figs. 6, 11 and 22) is carried in the totalizer frame 56 and supports the before described totalizer wheels 60. A spring-pressed pawl 195 (Fig. 12) is mounted on each of the totalizer wheels 60. The shaft 188 has a notch cut therein adapted to engage the pawls 195 as the shaft 188 rotates. When the operating crank 158 is turned, the cam 175 rocks the segment 178, which, through the pinion 180 and ratchet 181, rotates the gear 185 and shaft 187. The shaft 188 is turned by means of the universal coupling 189. The amount of movement transmitted to the shaft 188 by the cam 175 is sufficient to give the shaft one complete rotation. During the rotation of the shaft 188 the notch therein engages the pawls 195 and the totalizer wheels 60 are turned until they reach their zero positions. The amount of movement that each totalizer wheel 60 receives depends upon the position to which it has been set by the actuator segments when entering items. During total-printing operations the totalizer wheels 60 move the actuator segments 34 a distance equal to the movement they receive from the turn-to-zero shaft 188.

Zero stop mechanism

Mechanism is provided to prevent the totalizer wheels 60 from overthrowing, or in other words from passing the zero position if the machine should be operated too fast.

Formed on each totalizer wheel is a projection 200 (Figs. 6, 11 and 12). When the totalizer wheels are in the position shown in Fig. 6, they are setting at zero and the projections 200 are all in alignment. Two arms 201, connected by a bar 202, are loosely pivoted on a shaft 203. The bar 202 is adapted to be moved into the path of the projections 200 by a cam 207 (Fig. 7) before the totalizer wheels reach their zero positions. One of the arms 201 is slotted to receive a stud 199 mounted on an arm 204 (Figs. 6 and 7) secured to a shaft 205. The shaft 205 is carried by the side frames 44. Also secured to the shaft 205 is an arm 206 carrying a roller 210 adapted to project into the race of the cam 207 secured to the turn-to-zero shaft 182. It will be remembered that the turn-to-zero mechanism oscillates the shaft 182 during each total-printing operation of the machine. The link 179 (Fig. 10) of the turn-to-zero mechanism has a slot 208 which engages a stud in the before described segment 178. The stud on the segment 178 is held in engagement with the lower wall of the slot 208 by a spring 209. After all of the projections engage the bar, the link 179 is given a slight additional movement. However, the shaft 187 will have been stopped by the bar 202. It can therefore be seen that the slight overthrow of the link 179 insures the totalizer wheels reaching their zero positions and the bar 202 prevents overthrow thereof.

Total type wheel alining mechanism

It will be remembered that the bar 103 (Fig. 19) of the arms 102 and 107 alines the type wheels 38 for printing the items. The bar 103 is also used for alining the total type wheels 141 and an independent mechanism is furnished to operate it during total printing operations. Secured to the shaft 157, which receives a complete rotation during total printing operations, is the before described cam 110 into the cam race of which a roller on the pitman 109 secured to the arm 107 projects. The race of the cam 110 is so timed that it moves the bar 103 into contact with the pinion 96 after the type wheels 141 have been set and just before the total printing hammer makes the impression.

Total printing hammer

A hammer is provided for taking an impression from the total type wheels 141. This hammer is best shown in Fig. 19. Cut in the side of the before mentioned gear 160 is a cam race into which a roller on a downwardly extending arm 215 pivoted on a stud 216, 125 carried by the printer frame 98 projects. Also mounted on the stud 216 is an arm 217 secured to the arm 215 by means of a stud 218. The arm 217 carries a platen supporting channel bar 219 at its forward 130

end. An angle plate 220, secured to the printer frame 98, is adapted to engage a slot in the platen supporting channel bar 219 to guide it in a vertical path. The cam race in the gear 160 is so timed that the impression will be made just after the type wheels have been alined, as above described.

Type wheel turn-to-zero mechanism

- 0 Means is provided for returning the total printing type wheels to zero after the impression has been made, and after the totalizer has been disengaged from the actuator segments 34. This mechanism will now be described. Meshing with the before described pinions 140 (Fig. 19) are pinions 225, each of which has a slot 226, through which projects a rod 227 carried by two arms 228 secured to a shaft 229. Also secured to the shaft 229 is a pinion 230 (Fig. 21) meshing with the segment 231 pivoted on the stud 177. The segment 231 carries two rollers adapted to engage a double-plate cam 233 secured to the before described cam shaft 157. The cam 233 is formed to rock the two arms 228 first clockwise and then counter-clockwise, as shown in Fig. 21. The counter-clockwise movement of the arms 228 will take place after the totalizer has been disengaged from the actuator segments 34. The slots 226 are so located in the pinions 225 that the clockwise movement of the rod 227 will carry the type wheels 141 back to their zero or home positions. This movement, through the pinions 95 and 96, will return the actuator segments to their normal or home positions. The counter-clockwise movement of the arm 227 will have no effect on the gears 225 because at this time the rod is free to move idly in the slots 226.

Higher order registering segments

- 45 It will be noted that the machine as disclosed in the present application has three groups of keys and that the transaction totalizer has five totalizer wheels and the grand totalizer has seven totalizer wheels. Since there is but one actuator segment 34 for each group of keys it is obvious that it is necessary to provide a segment similar to the actuator segment 34 to set the total printing type wheels. The segment 34 for the tens of dollars type wheel, for each of the totalizers, is secured to the before mentioned shaft 70. 50 The segment 34 for the hundreds of dollars totalizer wheel is loosely mounted on the shaft 70 and meshes with the pinion 240 (Fig. 2) secured to the sleeve 241 which also has secured thereto, adjacent to the transaction totalizer, a pinion 242 (Fig. 3). The sleeve 241 extends through to the right hand end of the machine and has secured thereto a pinion 95 identical with those secured to the item type wheels 38. This pinion 95 meshes with a pinion 96, which in turn
- 55 meshes with a gear 140 secured to the hundreds of dollars type wheel.
- 60 The thousands of dollars segment of the grand totalizer is loosely mounted on the shaft 70 and meshes with a pinion 243, secured to the sleeve 244 carrying the pinion 95 meshing with the pinion 96 adapted to rotate the hundreds of dollars type wheel 141 through the gear 140. The segment 34 for the highest denomination totalizer wheel 75
- 65 engages a pinion similar to the pinion 243 pinned to the shaft 245 which shaft also carries a pinion 95 identical with those described for the lower order type wheels.
- 70 The pinions 95 associated with the higher order actuator segments 34 and 34' just described are provided with spring-pressed alining pawls 250 (Fig. 19). These are provided to prevent the segments 34 from moving out of alinement when the totalizers are 85 not engaged therewith.

Grand total printing operation

A mechanism is provided to select the grand totalizer for printing the total accumulated therein. The machine is normally set so that during transaction total printing operations the transaction totalizer will be engaged with the actuator segments and the grand totalizer will be prevented from engaging therewith. The means for preventing the grand totalizer from engaging the actuator segments will be first described. Secured on a sleeve 248 is an arm 251 (Figs. 1A, 22, 24 and 27) which carries a stud 249 normally engaging a hole in an arm 252'. The sleeve 248 has a slot through which projects a stud 254 secured in the shaft 166. A coil spring 258 is wound around the sleeve 248 between the pin 254 and the arm 165 secured to the sleeve. This spring holds the stud 249 in the arm 251 in engagement with the hole in the arm 252'. The arm 252' is adapted to engage the before mentioned spring-pressed plunger 57' (Fig. 26) which is provided with a cam edge 255' and a notch 256'. The grand totalizer engaging lever 55' (Figs. 1A and 26), which lever is like the lever 55 (Fig. 6) for the transaction totalizer, is adapted to engage the plunger 57' to rock the grand totalizer into engagement with the actuator segments when entering items. However, when totalizing from the transaction totalizer, the shaft 166 is rocked by the arm 167, as above described. This movement rocks the sleeve 248, which brings a cam edge 257' (Figs. 22 and 26) of the arm 252' into contact with the cam surface 255' of the plunger 57' and moves said plunger to the left (Fig. 26) and into a position in which the engaging lever 55' rocks idly into the before mentioned notch 256' in the plunger 57'. The arm 55' therefore has no effect on the grand totalizer and remains disengaged from the actuator segments.

When the arm 252' is rocked as just described a projection 285' (Figs. 22 and 27), thereon engages a stud 286' mounted in the grand totalizer frame 56', thereby locking said totalizer against accidental movement.

Grand totalizer selecting mechanism

A mechanism is provided to select the grand totalizer to print the total from the "grand" totalizer and disable the transaction totalizer. This mechanism will now be described. Pivoted on a bracket 260 (Figs. 1A, 6, 9, 22 and 24) is a lever 261 having a forwardly extending arm 264 having a cam surface 265. The sleeve 248 has an arm 266 (Figs. 1B, 6 and 22) having a stud 267 adapted to engage a hole 268 (Fig. 6) in the arm 252 of the transaction totalizer. When the lever 261 is rocked counter-clockwise, the cam surface 265 engages a beveled edge 269 on the arm 251, and shifts said arm, sleeve 248 and arm 266 toward the right far enough to disengage the stud 249 in the arm 251 from the arm 252' for the grand totalizer, and to engage the stud 267 on the arm 266 (Fig. 1B), with the hole 268 (Fig. 6) in the arm 252 for the transaction totalizer. When the crank 158 is operated with the lever 261 in the position just described, the arm 251 has no effect on the arm 252' of the grand totalizer, but the arm 266 rocks the arm 252 for the transaction totalizer. The cam 257 of the arm 252 for the transaction totalizer engages the cam surface 255 (Fig. 18) on the spring-pressed plunger 57 for this totalizer, thereby shifting the notch 256 into alinement with the totalizer-engaging arm 55 for the transaction totalizer. It can be seen that the grand totalizer then engages with the actuators, because its engaging lever 55' engages its plunger 57' and rocks it into engagement with the segments.

The turn-to-zero mechanism is normally disengaged from the grand totalizer. However, when the lever 261 is rocked as above described, for selecting the grand totalizer, a cam surface 263 on the arm 262 engages a beveled edge 287 of a clutch member 270 (Figs. 1A, 22 and 23). This engages the clutch member 270 with a clutch member 271, which is operatively connected to the turn-to-zero shaft 188 by a flexible or universal coupling 272. The clutch member 270 is secured to the turn-to-zero shaft 188' for the grand totalizer. From this it can be seen that when the machine is operated from the operating crank 158 the totalizer wheels for the grand totalizer will be turned to zero in identically the same manner as is done when clearing the totalizer wheels for the transaction totalizer, as above described.

The turning to zero of the totalizers is accomplished as an incident to printing the totals from the totalizer, and only one total can be printed during a single operation of

the machine. Inasmuch as the same turn-to-zero shaft is used for both totalizers, it requires two separate operations to print the total on both totalizers. The turn-to-zero shaft runs through the "transaction" totalizer, and selectively connects with the "grand" totalizer for printing from the grand totalizer, and therefore, when the totalizer elements for the grand totalizer are rotated to zero, the transaction totalizer wheels are also rotated. But by first printing the total from the transaction totalizer before printing the total of the grand totalizer, the transaction totalizer wheels are standing at zero at the start of the grand totalizer turn-to-zero operation. During the grand totalizer turn-to-zero operation, the transaction totalizer elements are given a complete rotation, but this rotation of the transaction totalizer elements is an idle one since the elements are not in mesh with the actuator segments 34 of the transaction totalizer. For these reasons the transaction totalizer must always be turned to zero before the grand totalizer is turned to zero.

A mechanism is also provided to keep the clutch members 270 and 271 in positive engagement during the complete rotation of the turn-to-zero shaft. Secured to the turn-to-zero shaft 188' is a disk 275 (Figs. 1A, 6 and 22) having a notch 276. Secured to the grand totalizer frame is a bracket 277 having a downwardly projecting flange 288 so formed that it normally engages the notch 276 in the disk 275, thereby preventing the turn-to-zero shaft 188' for the grand totalizer from being turned. However, when the turn-to-zero shaft is shifted to the right to engage the clutch members, the flange 288 of the bracket 277 is disengaged from the notch 276 and is in alinement with the left side of the disk 275. After the turn-to-zero shaft 188' has started to turn it cannot shift to the left until it has made a complete rotation, at which time the notch 276 and flange are again in alinement. When the lever 261 is again moved to select the transaction totalizer, and the arm 262 is rocked out from between the clutch member 270 and the totalizer frame 56, a spring 289 will return the disk 275 towards the left, thereby disengaging the clutch members 270 and 271.

A bar 202' identical with the bar 202 provided for the transaction totalizer is provided for the grand totalizer, except that it is wide enough to take care of seven totalizer wheels instead of five, as is the case in the transaction totalizer. This bar is rocked by the shaft 205 in the arm 204 in the same manner as that described for the transaction totalizer.

An interlocking device is provided for the lever 261 so that the lever cannot be moved after the crank 158 has been started. The arm 264 of the lever 261 has a flange 280

(Figs. 1A, 9 and 22) adapted to cooperate with a flanged arm 281 secured to the before described sleeve 248. It will be remembered that at the beginning of any total printing operation the sleeve 248 is given a counterclockwise movement which will position the flange on the arm 281 in the path of the flange 280 on the arm 264. If the lever 261 has been moved to select the grand totalizer, the flange of the arm 281 will pass over the top of the flange 280, thereby preventing the lever 261 from being returned until after the total printing operation is complete. When the totalizer selecting lever 261 is in the normal position, as shown in Fig. 9, that is, before it is shifted to select the grand totalizer, and a total is taken of the transaction totalizer, the flange on the arm 281 rocks beneath the flange 280, thus preventing shifting of the selecting lever 261, during transaction total taking operations.

Operation

A brief description of the operation will now be given. The operator will enter amounts in the transaction totalizer and the grand totalizer simultaneously when depressing the amount keys 30. This will set the amount on the item printing type wheels and print on the inserted slip. Any number of items can be entered in the totalizers before the total is printed. After all of the items of a given transaction have been entered the operator will turn the totalizer crank, which will engage the transaction totalizer with its actuator segments and turn the totalizer wheels to zero. This turn-to-zero movement is transmitted to the total printing type wheels by means of the actuator segments and the associated type line. After the amounts have been set up in the type wheels the total printing hammer will print the total and the transaction will be completed.

When it is desired to print a grand total of a number of transactions a total selecting lever is moved which will disable the totalizer engaging mechanism for the transaction totalizer and render the engaging mechanism for the grand totalizer operative, whereupon the operator will turn the crank and the total will be printed from the grand totalizer in a manner identical with that just described for the transaction totalizer.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination of accumulating elements, means for turning the accumulating elements to zero, actuators for entering items into the accumulating elements adapted to be moved by the accumulating elements when said elements are being turned to zero, said movement being in the same direction when being turned to zero as when entering items, and printing elements arranged in complementary relation with the accumulating elements and actuated by the said actuators for printing totals. 70 75

2. In a machine of the class described, the combination of accumulating elements, means for turning the accumulating elements to zero, actuators for entering items into the accumulating elements adapted to be moved by the accumulating elements when said elements are being turned to zero, said movement being in the same direction when being turned to zero as when entering items, and printing elements arranged to be set by the item entering actuators to print amounts corresponding to the complement of the amount of movement given the accumulating elements when said elements are turned to zero. 80 85 90

3. The combination of a shaft, a notched member secured to said shaft, a pivoted device operatively connected to the notched member, a member carrying said pivoted device, means for rotating the second mentioned member for turning the shaft, and means for rocking the pivoted device for partially turning the 100 shaft. 95

4. The combination of a shaft, a device secured to said shaft, a member rotatably mounted on said shaft, means for coupling said member to said device for giving the 105 shaft a complete rotation, and means for operating the coupling means for giving the shaft an oscillating movement.

5. The combination of a totalizer, actuators therefor, a shaft, means on the shaft for 110 engaging the totalizer with the actuators, a device secured to said shaft, a member adapted to be rotated on said shaft, means for coupling said member to said device for rotating the shaft, and a device for operating the 115 coupling means for partially rotating the shaft.

6. In a machine of the class described, the combination of a plurality of totalizers, a group of actuators for each totalizer, a means for engaging each totalizer with its actuators for printing totals, total printing mechanism, operating means for the total printing mechanism, means operable by said operating means for actuating the totalizer engaging 120 means, and a member for controlling the effectiveness of the totalizer engaging means. 125

7. In a machine of the class described, the combination of a plurality of totalizers, actuators for each totalizer, a lever for each total- 130

- izer adapted to move the totalizer into engagement with its actuators, a spring-pressed plunger mounted on each totalizer adapted to be engaged by said levers, said plungers each having a notch, total printing mechanism to take totals from said totalizers, operating means to operate the total printing mechanism, an arm for each totalizer operated by said operating means, for shifting the plungers to position the notches into the paths of the levers whereby the levers become ineffective, and a device for determining the effectiveness of said arms.
8. In a machine of the class described, the combination of a plurality of totalizers, actuators for each totalizer, a lever for each totalizer adapted to move the totalizer into engagement with its actuators, a spring-pressed plunger mounted on each totalizer, adapted to be engaged by said levers, said plungers each having a notch, total printing mechanism to take totals from said totalizers, operating means for the total printing mechanism, an arm for each totalizer for shifting the plungers to position the notches into the path of the levers whereby the levers become ineffective, a rockable shaft loosely supporting said arms, a sleeve slidably mounted on said shaft and adapted to be rocked thereby, members secured to the sleeve and adapted to engage the arms, a device for shifting the sleeve to determine which of said members is to engage said arms, and means operated by said operating means for rocking the shaft.
9. In a machine of the class described, the combination of a grand totalizer, a transaction totalizer, a turn-to-zero shaft for the transaction totalizer, a turn-to-zero shaft for the grand totalizer, means for locking the turn-to-zero shaft for the grand totalizer, total printing mechanism for printing totals on either totalizer, and a manipulative device for determining when a total is to be printed from the grand totalizer for clutching the two turn-to-zero shafts together for simultaneous operation, and for unlocking the turn-to-zero shaft for the grand totalizer.
10. In a machine of the class described, the combination with a totalizer, actuators therefor, and means for engaging the totalizer with the actuators, of a rotatable shaft, engaging means on the shaft for engaging the totalizers with the actuators, means for rotating the engaging means and the shaft during item entering operations to engage the totalizer with the actuators, and means for oscillating the engaging means and the shaft during total taking operations to engage the totalizer with the actuators.
11. In a machine of the class described, the combination of accumulating devices, actuators therefor, item recording elements adjusted by said actuators, total recording elements, connections between the total recording elements and said item recording ele-

ments, and means for engaging the accumulating devices with the actuators during total recording operations to adjust the item recording elements and through said connections adjust the total recording elements.

12. In a machine of the class described; in combination with accumulating elements; actuators for entering items into the accumulating elements; printing elements for recording the items entered into the accumulating elements; and a printing platen to take impressions from the item printing elements; of total printing elements geared to the item printing elements; and total taking mechanism adapted to set the total printing elements through the item printing elements.

13. In a machine of the class described; in combination with accumulating elements; actuators for entering items into the accumulating elements; and item printing elements for recording the items entered into the accumulating elements; of total printing elements with numerals arranged complementary to the numerals on the item printing wheels, said total printing elements being adjusted through the item printing elements; and connections between the item printing elements and the actuators to simultaneously adjust both sets of elements when entering items and when printing totals.

14. In a machine of the class described, in combination with a plurality of totalizers; a set of actuators for each totalizer; engaging means for each totalizer adapted to normally engage the totalizers with their respective actuators; and control means to determine the effectiveness of the engaging means; of slidable means adapted to be coupled to one of the control means; and mechanism to operate the slidable means to selectively operate one of the control means to render the engaging means for one totalizer ineffective.

15. In a machine of the class described, in combination with a plurality of totalizers; a set of actuators for each totalizer; engaging means for each totalizer adapted to normally engage the totalizers with their respective actuators; and control means to determine the effectiveness of the engaging means; of slidable means adapted to be coupled to one of the control means; a manually operable lever to control the movement of the slidable means to determine the position of the slidable means; and mechanism to operate the slidable means to selectively operate one of the control means to render the engaging means for one totalizer ineffective.

16. In a machine of the class described, in combination with a plurality of totalizers; a set of actuators for each totalizer; engaging means for each totalizer adapted to normally engage the totalizers with their respective actuators; and control means to determine the effectiveness of the engaging means; of slidable means adapted to be coupled to one of

the control means; a cam surface on the slide-
able means; a manually operable lever; a cam
on the lever to engage the cam surface on the
slideable means to control the position of the
slideable means; and means to operate the
slideable means to selectively operate one
of the control means to render the engaging
means for one totalizer ineffective.

17. In a machine of the class described, the
10 combination of accumulating elements, total
printing elements, item entering actuators in-
terposed between the accumulating elements
and the total printing elements to set the
total printing elements complementally by
15 the accumulating elements when the accumu-
lating elements are reset, and means to reset
the accumulating elements by turning them
in the same direction as when entering items.

18. In a machine of the class described, the
20 combination of a totalizer, actuators there-
for; item printing elements; total printing
elements arranged in complementary relation
with the item printing elements; and means
25 always connected with the actuators to set
up the items as they are entered, and to set
up the totals standing on the totalizer when
taking totals.

19. In a machine of the class described, the
combination of accumulating devices; means
30 for restoring the accumulating devices to
zero; actuators for entering items into the
accumulating devices, said actuators adapted
to be moved by the accumulating devices,
when the devices are being restored to zero,
35 in the same direction as the actuators are
turned when adding into the accumulating
devices; item recording elements adjusted by
said actuators; total recording elements ar-
ranged in complementary relation with the
40 item recording elements; connections be-
tween the total recording elements and the
item recording elements; and means for en-
gaging the accumulating devices with the
actuators during total recording operations
45 to adjust the item recording elements and
through said connections adjust the total re-
cording elements according to the comple-
ment of the restoring movement of the ac-
cumulating devices.

50 In testimony whereof I affix my signature.
WILLIAM H. ROBERTSON.
